UNITED STATES PATENT OFFICE.

PHILIP N. SEA, OF ROCKFORD, ILLINOIS.

PORTABLE FILE.

Application filed November 9, 1925. Serial No. 67,710.

My invention relates to portable file outfit, particularly to an outfit in which is used the filing device of my Patent No. 1,381,937, dated June 21, 1921. The filing device of the patent referred to comprises a bottom cover member and a top cover member, said members being hinged at their rear edges to a non-foldable back part to which leaves are hinged at spaced intervals to leave spaces for the storage of papers or other material, such back part being free to assume various angles of inclination relative to the cover members depending upon the amount of material inserted between the leaves, so that the leaves may at all times remain horizontal when the device is laid flat on a support, the leaves being all of the same length so that when the back part is at an angle with the cover members, index tabs secured along the outer edges of the leaves will become visible for reference.

The important object of my invention is to incorporate the filing device of the patent referred to in vertical position in a container such as a portfolio or salesman's reference case. In this use of the filing device it preferably normally rests on its back part with the cover members and partition leaves extending vertically, and in accordance with my invention I so construct the container that the filing device can be readily shifted therein and supported in position with its back or bottom part at an angle to cause overlapping of the upper ends of the leaves and exposure of the index tabs so that the contents of the filing device can be readily located and referred to.

The invention is clearly illustrated on the accompanying drawing in which, Figure 1 is a vertical transverse sectional view of a containing case and the index device therein;

Fig. 2 is a similar view showing the container opened and the filing device raised into tab exposing position;

Fig. 3 is a perspective view of the lower section of the container case showing the arrangement for supporting the filing device in normal or exposed position, and

Fig. 4 shows a modified arrangement.

The filing device shown comprises the cover members 10 and 11, the bottom wall 12 to which the cover members are hinged, and the leaves or partition walls 13 se-

cured to the bottom wall 12 at spaced intervals to form compartments for materials to be filed.

The container case shown may be constructed of leather or other suitable material and is of rectangular cross section, being provided at its top with the closure frame 14 and with handles 15. The filing device may take up the entire case or occupy only a section thereof. When occupying the whole case, the bottom wall 12 of the filing device will be of the same width as the bottom of the case, on which bottom the wall 12 normally rests as shown in Figure 1, and in which position the cover members 10 and 11 and the partition walls will terminate below the closure frame 14 so that this frame can be closed. When it is desired to use the filing device, the case is opened and the cover members 11 of the device is raised along the adjacent wall 16 of the case. Such raising of the member 11 will raise the bottom wall 12 to inclined position and will bring the upright walls of the device in overlapping positions at the top of the case so that the index tabs 17 will be exposed. Such positioning of the filing device will decrease its thickness, and in order to hold the device in its exposing position, an abutment 18 is provided at the bottom of the case against which the joint between the cover member 10 and the bottom wall 12 may abut and rest in order to hold the filing device in its upper and exposing position. The abutment could be one side of a groove 19 extending longitudinally in the bottom of the case and such groove could conveniently be provided by leather strips 20 and 21 secured against the bottom of the case and spaced at their inner edges to leave the groove 19. These strips 20 and 21 will then form a horizontal seat for the wall 12 of the filing device when the case is to be closed, and when the case is opened and the cover member 11 of the device is raised, the joint between the cover member 10 and the bottom wall 12 will readily slide into the groove 19 and against the abutment 18 to lock the device in its service position. When it is desired to restore the device to a normal position the member 10 thereof is lifted sufficiently to withdraw its lower edge from the groove 19 and then the weight

of the materials in the device will cause it to assume its normal position with its wall 12 seating against the case bottom.

As shown in Fig. 4 a number of grooves 5 22 may be provided by strips 23 for holding the bottom wall 12 in various angular positions depending upon the amount of material held in the file.

My improved structure and combination 10 provides a very desirable and convenient outfit which can be efficiently used by salesmen, contractors, business men, and for general purposes.

I do not desire to be limited to the precise construction and arrangement shown 15 and described as modifications can be made which would still be included in the invention which I claim as follows:—

1. In combination, a filing device comprising cover members, a bottom wall hinged to the lower edges of said cover members, and leaves hinged to said bottom wall at spaced intervals to form filing compartments, a case in which said filing device 20 normally rests with its bottom wall flat against the case bottom, and an abutment on the bottom of the said case for receiv-

ing one edge of said bottom wall and for holding said bottom wall in an inclined position with its other edge against the rear 30 wall of said case.

2. In combination, a filing device comprising cover members, a bottom wall hinged to the lower edges of said cover members, leaves hinged to said bottom wall at spaced 35 intervals to form filing compartments, a case in which said filing device normally rests with its bottom wall flat against the case bottom, and an abutment on the bottom of said case for receiving one edge 40 of said bottom wall when said filing device is raised by an upward pull of the cover member at the other edge of said bottom wall, said cover member then resting against one side of said case with said leaves 45 overlappingly extended at their upper ends, upward pull of the opposite cover member of said filing device causing said bottom wall and first mentioned cover member to assume their normal positions. 50

In witness whereof, I hereunto subscribe my name this 5th day of November, 1925.

PHILIP N. SEA.
